UNITED STATES PATENT OFFICE.

HAMPTON P. RHODES, OF SHREVEPORT, LOUISIANA.

PISTON-ROD PACKING.

SPECIFICATION forming part of Letters Patent No. 770,926, dated September 27, 1904.

Application filed April 29, 1904. Serial No. 205,591. (No model.)

To all whom it may concern:

Be it known that I, HAMPTON P. RHODES, residing at Shreveport, in the parish of Caddo and State of Louisiana, have invented a new and Improved Piston-Rod Packing, of which the following is a specification.

My invention relates to improvements in that class of rod-packing improvements in which metallic packing members are mounted 10 within the stuffing-box arranged to be snugly held up against the rod to provide for tightly packing the same.

In its generic nature my invention embodies a series of ring-segments formed of metal that are 15 flexibly connected in such manner whereby the several segments in each ring will be held in such coöperative relation as to provide a substantial continuous circular bearing or packing surface and in such manner that 20 the several segments in a section act as a solid metal ring, possessing, however, such pliability as is usually found in soft-material bearing-rings, whereby to open and close around rods of slightly-irregular diameters, and there- 25 by automatically expand or contract with respect to the rods as the varying thicknesses or irregular peripheral surfaces thereof may make necessary to provide for a proper packing.

30 In its more complete make-up my invention embodies a stuffing-box and an annular cushion held within the bore of the stuffing-box, which may be formed of a single member or in sections joined to produce a circular member, 35 said cushion having a plurality of horizontal flanges each adapted to fit between a pair of superposed metallic ring-sections to hold the said metallic ring-sections from contacting with each other and from engaging the side 40 of the stuffing-box, said annular cushion being also provided to form a yielding surface to take up the radial expansion of the rings to provide the required elasticity for holding the said metal bearing-rings against the rod.

45 Furthermore, my invention, in addition to the annular cushion and the segmental rings before referred to, includes a supplemental cushioning means of a substance harder than the main cushioning member arranged to en- 50 gage the peripheral edges of the several me-

tallic packing members in such manner as to cause them to fit square against the piston-rod and to also close the joints between the several parts to effectually prevent escape of steam or any other fluid—such as oil-ammonia, 55 water, or gas—through the stuffing-box.

In its more subordinate features my invention consists in certain details of construction and novel combination of parts that are so co-operatively arranged that they can be economically and easily manufactured, which will serve for the purpose intended, and which can be readily adjusted for use, all of which will be hereinafter fully described, specifically 60 pointed out in the appended claims, and illustrated in the accompanying drawings, in which—

Figure 1 is a vertical section of the stuffing-box with my improved packing applied for use. Fig. 2 is a top plan view thereof 70 with the gland or cap member removed. Fig. 3 is a horizontal section thereof, taken practically on the line 3 3 of Fig. 4. Fig. 4 is a similar view taken on the line 4 4 of Fig. 1. Fig. 5 is a detail perspective view of one set 75 of metal packing-segments that constitute a complete packing. Fig. 6 is a detail perspective view of one of the segments of said ring. Fig. 7 is a perspective view of one set of cushion rings or holders with their coacting metallic ring-segments and illustrating a preferred construction of the said cushion-ring. Fig. 8 is a perspective view of a modified form of cushion or holder, said holder being shown as composed of semicircular 80 solid members, the said members, together with the metal rings supported thereby, being shown separated. Fig. 9 is a detail perspective view of one of the cushion or holder members shown in Fig. 8. Fig. 10 is a detail view of one of the supplemental cushion-rings hereinafter referred to.

In the drawings, 1 designates the stuffing-box, which is of the usual construction, 2 the gland thereof that enters the box at one end, 95 the top in the present illustration, and which is adjustably pressed down against the internally-held packing device presently explained by the adjusting-bolts 15 15, and the bottom of the box 1 has a central aperture 1^a for the 100

rod 3, which also plays in the central bearing 2^a in the gland, as usual.

My improved packing device comprises a holder A of special design, formed of a cushioning or elastic material, such as hard rubber or soft rubber mixed with asbestos or other suitable material capable of being compressed into a solid body having a stiff elastic or cushioning action under pressure. Each holder A 10 carries a number of arbitrarily-arranged metallic packing members B, which are connected with the holder A in such manner that the said holder, together with the packing members supported therein, can be readily fitted 15 as a whole into or withdrawn from the stuffing-box. The holder A in the preferred construction is made of sections, preferably two semicircular sections, as shown in Fig. 8, the ends a a of which are adapted to tightly abut 20 to form square shoulders, and the said holder A has a diameter to snugly fit with its perpendicular or circumferential edge a' tightly against the inner wall of the stuffing-box. The holder A in my arrangement of packing 25 devices acts as a vibratory or radial expandable member to permit the piston-rod 3 to run out of true alinement, the same as if the rod were in a perfect condition. Each section of the holder A consists of a thick vertical portion 1^x and an upper and lower inwardly-extended horizontal annular flange a², the upper face of the lower and the under face of the upper flange being concaved, as at a³, from the part a' to the inner or rod-engaging end for 30 reasons presently explained. Each holder A, as shown, is arranged to hold two sets of metallic packing-rings B B; but I desire it understood the said holder A may be formed with a greater number of flanges a² to receive 40 a greater number of metallic rings B.

Each packing-ring B consists of a number of segmental sections b, which may have three sections of like size or a greater number of sections b' b' of different sizes, as shown in 45 Fig. 5, but of such correlative size that when joined they make a complete ring. The several metallic sections B are linked together at the ends by a flexible connection C, which may be and preferably is a piece of soft-metal 50 rod-wire, the opposite ends of which are molded in the abutment ends b⁵ of the ring-sections. The connection C in practice may, however, be of any soft material that will not scratch the piston-rod should it come into contact therewith. The said rings B have such 55 internal diameters that their bearing edges b³ constitute a circle much less than the internal diameters of the holders A, such correlative sizes of the rings B and the holders A being 60 provided so that only the edges of the metal rings B are held to engage with the rod 3. By joining the metal ring-sections in the manner stated the same will be held as a solid ring and having such pliable adjustment as to act on 65 the rod 3 substantially the same as does a soft

packing-ring, and to provide for a perfect solid bearing for the rod the several rings B in each holder are so positioned that the joints of one ring break with the joints of the adjacent ring, as shown.

The several ring members in each holder A are held out of engagement with each other, and for such purpose each section has a flat surface x, that terminates in a convexed face x', and the convexed surface x of the said ring is so arranged as to snugly seat within the concaved surface of the flange a² of the holder, with which the respective metallic surfaces engage, the convexed concavo fitting of the ring-sections and the flanges serving to aid in holding 70 the several rings B square against the piston-rod, whereby to prevent leakage between the said rod and the packing-rings. Each ring-section is also provided with an annular square shoulder 4. In fitting the two metal rings with 75 in the holder A they are so positioned that their annular shoulders 4 oppose each other, whereby to form, as it were, an annular groove D between the opposing rings B and the adjacent cushion-wall and square in cross-section. 80 Within the annular groove D is tightly fitted a ring E, square in cross-section, of a pliable substance, much harder, however, than the cushion B and the said ring, which may consist of semicircular sections or be of a greater 85 number of segments, if desired. The rings E, together with the concaved convexed contacting surface between the rings and the holder-flanges, serve to maintain the metal rings B square against the piston-rod 3 and hold the said metal rings in position, as well as providing for adjusting the said rings from 90 time to time.

By providing the peculiar arrangement of 95 metal rings B and supporting them within the peculiarly-constructed cushion-body holders A the several metal rings are so held with respect to each other and to the holders A as to provide fluid-tight connections that prevent any leakage whatever, and thereby reduce the danger of decaying the cushion to the minimum.

While I have shown but two holders A, with 105 their coacting metal packing-rings, it is manifest a greater number of said holders may be provided. The arrangement of the holder and the rings admits of easily fitting the several parts within the stuffing-box or for removing them and also for conveniently adjusting the several rings within their respective 110 holders.

After the holders with their rings have been 115 inserted within the stuffing-box the several holders may be tightly clamped into position by forcing down the gland in the manner 120 clearly explained in Fig. 1.

Having thus described my invention, what I claim, and desire to secure by Letters Patent, is—

1. A rod-packing comprising an annular 130

holder formed of an elastic material and adapted to snugly fit within the stuffing-box, said holder having a plurality of inwardly-projecting annular flanges at each side and a central flange disposed midway said side flanges, metallic packing-rings detachably supported between the said side and central flanges of the holder with their inner or bearing surfaces projected beyond the inner edge of the holder substantially as shown and for the purposes described.

2. A rod-packing which comprises an annular holder formed of an elastic material, said holder having side and central annular flanges, a series of metallic bearing-rings detachably supported on the holder in superposed positions and between said flanges, the internal diameters of the said rings being less than the internal diameter of the holder-flanges, said rings being so connected with the holder as to be moved with the holder from within the stuffing-box.

3. A rod-packing of the character described, comprising a holder formed of an elastic body provided with inwardly-extended horizontal flanges, a plurality of metallic rings having a superposed relation detachably supported by the holder between the horizontal flanges thereof, each of said rings consisting of segmental members flexibly joined at the ends and provided with a right-angled groove on the peripheral edge thereof, and a supplemental elastic ring adapted to fit within the said right-angled groove of the metallic rings and to bear against the adjacent wall of the elastic holder, all being arranged substantially as shown and for the purposes described.

4. In a rod-packing of the character described, a holder formed of an annular-shaped elastic body adapted to snugly fit within a stuff-

ing-box, and a series of metallic rings detachably supported upon the said holder, said metallic rings being projected beyond the inner edge of the holder, the said metallic rings consisting of segmental sections, said segmental sections having pins at one end and bores at the other ends, said pins and bores coöperating with each other to serve to hold the sections loosely together substantially as shown and for the purposes specified.

5. The hereinbefore-described improved rod-packing which consists of a holder formed of an annular-shaped elastic body composed of segmental sections, each of said sections having an upper and a lower inwardly-projected flange, the inner faces of said flange being concaved, a supplemental elastic ring formed of sections located on the inner face of the holder at a point midway the horizontal flanges, at the opposite ends thereof, and a pair of metal rings, said rings having convexed surfaces to engage the concaved surfaces of the holder-flanges and provided with right-angled grooves in their peripheral edges, the said rings being disposed with their right-angled grooves opposing each other whereby to form an annular groove square in cross-section adapted to receive the supplemental elastic ring, the said metal rings being formed of segmental sections, the abutting ends of which are flexibly joined, the joints of the several segments of one ring being arranged intermediate of the joints in the adjacent ring, all being arranged substantially as shown and for the purposes described.
